United States Patent

Des. 242,503
Patented Nov. 30, 1976

242,503

COMBINED BIB AND PACIFIER

Lois B. Derifield, 102 Tooke St.,
Fort Walton, Fla. 32548

Filed May 14, 1975, Ser. No. 577,474

Term of patent 14 years

Int. Cl. D2—05

U.S. Cl. D2—226

The figure is a front elevational view of a combined bib and pacifier showing my new design, the rear thereof being plain and unornamented.

I claim:

The new and ornamental design for a combined bib and pacifier, as shown and described.
